UNITED STATES PATENT OFFICE

DANIEL J. HURLEY, OF DETROIT, MICHIGAN

REFRIGERATOR BOX

Application filed December 28, 1928. Serial No. 328,459.

This invention relates to improvements in refrigerator boxes, and aims, among other things, to provide a light yet strong type of box made of very few parts, and having at least a partial vacuum between its inner and outer walls so that a high degree of insulation is obtained.

Other objects of the invention are: to provide a refrigerator box wherein the sheets which compose the walls are corrugated to increase their strength; wherein bracing members are positioned between the walls transversely of the corrugations to further strengthen them against buckling, and to do so in such a manner that only very small contact areas occur between the inner and outer sheets; wherein a cheap and simple form of mounting arrangement for hinges and other fittings is provided which is so constructed that there is practically no possibility of air entering around them to destroy the partial vacuum between the walls.

With these and other objects and advantages in view, which will become apparent as the specification proceeds, the invention, which resides in certain novel construction and combination of parts, is hereinafter more fully described with the aid of the accompanying drawings, in which:

Figure 1 illustrates a front elevation of the invention.

Figure 2 is an enlarged section on the line 2—2 of Figure 1.

Figure 3 is a broken, enlarged section on the line 3—3 of Figure 1, and

Figure 4 is a section on the line 4—4 of Figure 2.

Figures 5 and 6 show details which are further enlarged and the latter figure is in perspective.

Referring to the drawings, 1 designates a box consisting of an inner wall 2 and an outer wall 3. The top 2a, sides 2b and bottom 2c of the inner wall 2 are preferably made of one piece of material welded transversely

at its ends as indicated at 2d. Similarly the top 3a, sides 3b and bottom 3c of the outer wall 3 are also usually made of one piece of material which is generally welded transversely of the box as indicated at 3d. It will be noted that the sheets out of which the walls 2 and 3 are fabricated are corrugated; that corrugations 2e continue around the top 2a, sides 2b and bottom 2c and extend outwardly; and that corrugations 3e run around the top 3a, sides 3b and bottom 3c and project inwardly. The corrugations 2e and 3e should be positioned opposite to one another and be of such section that their inner sides are substantially continuous to one another throughout the greater part of their depth. This form of corrugation not only affords a great deal of strength, but also reduces the radius of their outer ends 2f and 3f. Arranged at intervals between the corrugations 2e and 3e so that their axes lie substantially at right angles to the direction of the corrugations, and in contact with the latter, are a plurality of rods 4, preferably of circular section which are usually welded in position to the outer ends 2f of the corrugations. These rods act as spacing members between the inner and outer corrugations 2e and 3e, and, owing to the very small contact areas between the peripheries of the rods and the outer ends of the corrugations the thermal conductivity between them is very slight. The front portions 2g and 3g of the sheets 2 and 3 are in-turned to form a doorway 7f, and the margin 3h of the portion 3g is rearwardly flexed and welded to the outer margin of the portion 2g at 2h.

The back of the box consists of an inner sheet 5 and an outer sheet 6. The sheet 5 has outward corrugations 5a and is of such size that its edges rest against the rear margins of the inner wall 2, to which it is welded. It will be noted that in the present instance the rear margins of the side walls 2b are inwardly flexed to form bearing surfaces for the 90

side margins of the back sheet 5, and that the top and bottom walls 2a and 2c terminate at right angles to the sheet 5 to the top and bottom margins of which they are attached. The outer back sheet 6 is usually flat and has a plurality of substantially T-shaped reinforcing members 6a welded, or otherwise suitably secured to its inner side. These members 6a should be positioned substantially at right angles to the corrugations 5a and should bear against the outer ends of the latter. In this manner the inner and outer sheets 5 and 6 are supported against collapsing, and a tendency to do so is caused when a partial vacuum occurs between these sheets. The partial vacuum and the preferred means of obtaining it are referred to hereinafter. This arrangement of contacts between the reinforcing members and the corrugations so reduces the contact areas that very slight thermal conductivity occurs between the sheets. The margins of the back sheet 6 are welded to the rear margins of the outer wall 3 in a manner similar to that employed for securing the sheet 5 to the inner wall 2. The upper and lower ends of the corrugations 5a are welded closed as shown at 5b to keep the interior of the box airtight from the space between the inner and outer back sheets 5 and 6.

From the foregoing construction it may be seen that the inner portion of the box 2 and its back 5 may be assembled and afterwards inserted into the outer portion 3, and then the outer back sheet 6 then secured in position.

The door 7 consists preferably of an inner plate 7a having its outer portions outwardly flared at 7b to form a joint against the outer wall portions 3b, and its margins 7c are flexed substantially into line with the main portion. The outer door plate 7d is preferably flat and is provided with an inturned annular margin 7e to form a receiving groove for the margins 7c of the inner plate 7a. In order to maintain an airtight joint between the inner and outer plates the latter are usually welded around the edge of the inturned margin 7e as indicated at 7f. On the inner side of the door plate 7a substantially T-shaped strengthening members 8 are secured, and rods 9 are attached to the inner side of the outer plate 7d with their axes substantially at right angles to the direction of the said members. The adjacent sides of these rods and strengthening members rest against each other and tend to hold the door against collapsing if a partial vacuum occurs between the door plates, and at the same time the contact areas between the rods and members are very small. 10 denotes a resilient annular pad arranged between the door 7 and the sides of the box against which the door margins close to assist in maintaining an airtight joint when the door is shut.

I will now describe a simple form of mounting device 14 for holding a hinge member 11,

rack supports 12 and refrigeration unit holding bolt, one of which is shown at 13. Firstly a hole 15 is cut through the plate, as through the plates 3 and 7d shown in Figure 5. Around this hole an annular depression 16 is formed. Through the hole 15a sleeve 20 is inserted which is threaded internally and, in this case, has a closed end wall 17. Around the outer end of the sleeve is an annular flange 18 of lesser diameter than the depression and of substantially the same thickness as the depth of the latter. The mounting is held in place by welding at 19 around the periphery of the flange and to the depressed plate portion. Fittings as for instance hinge members 11 are held in position by screws 21 which are in threaded engagement with the sleeve bore. Rack supports 12 and the bolt 13 are threaded directly into the sleeves.

After the box has been assembled it is usually enamelled. In order to dry the enamel the box is submitted to heat. 25 and 25a designate valves mounted in the inner wall 2 and inner door plate 7a respectively. They are preferably held by mountings 14a similar to the mountings 14 already described except that openings 17a are formed through the end walls 17 of the sleeves 20. While the box is being submitted to heat these valves are opened, and, before the box cools, they are closed, and as shortly thereafter as possible these valves are welded or soldered shut in such manner as to preclude the possibility of air entering the spaces between the inner and outer walls or plates. Owing to the fact that the air in these spaces was at a high temperature when the valves were closed a partial vacuum of course results when the box cools. The provision of a partial vacuum adds to the insulation and to the efficiency of the box for the purpose intended, though if dead air lies between the walls and plates a quite satisfactory structure results.

While in the foregoing the preferred construction of the invention has been described and shown, it is understood that I may make alterations and modifications thereto provided said alterations and modifications fall within the scope of the appended claims.

What I claim as my invention and desire to secure by Letters Patent is:

1. In a box of the character described, the combination of inner and outer walls spaced from one another, the outer walls being inwardly corrugated and the inner walls being outwardly corrugated; the corrugations in one wall being substantially in alignment with the corrugations in the wall spaced from it, and a plurality of substantially circular rods extending between each pair of spaced walls transversely of their corrugations, each rod on one side being secured at intervals to the outer extremities of the corrugations on one wall and its opposite side being secured

at intervals to the outer extremities of the corrugations of the wall spaced from it, so that said rods hold each pair of spaced walls in their correct spaced relationship.

5 2. In an arrangement of the character described, the combination of a container having double walls spaced from one another, one wall having a plurality of members of T-section secured against one of its sides, the
10 other wall having a plurality of substantially circular rods secured against it, said rods being arranged transversely relative to said members, and having portions of their peripheries secured to the outer extremities
15 of said members.
